INVENTOR

UNITED STATES PATENT OFFICE

98,415

DESIGN FOR A DRESS

Charles Baum, Woodmere, N. Y.

Application January 8, 1936, Serial No. 60,470

Term of patent 3½ years

To all whom it may concern:

Be it known that I, Charles Baum, a citizen of the United States of America, residing in Woodmere, county of Nassau, and State of New York, have invented a new, original, and ornamental Design for a Dress, of which the following is a specification, reference being had to the accompanying drawing, forming part thereof, wherein,

The vertical lines extending down the front waist and skirt portions of the dress represent strips of pipings.

I claim:

The ornamental design for a dress, substantially as shown and described.

CHARLES BAUM.
